JOSEPH W. DAWSON AND JAMES L. HEROLD, OF ST. LOUIS, MISSOURI, ASSIGNEES TO BARRY-WEHMILLER MACHINERY COMPANY, OF ST. LOUIS, MISSOURI, A CORPORATION OF MISSOURI.

BOTTLE-WASHING MACHINE.

Application filed December 18, 1922. Serial No. 607,527.

This invention relates to improvements in bottle washing machines, and the object is to produce a novel and highly efficient means for washing bottles both interiorly and exteriorly. Prior to this invention a number of machines had been produced which washed the interiors of bottles by injecting streams of water into said bottles, but many of these devices failed to attain the desired efficiency, due to the failure of the streams to be projected into the bottles with sufficient force to thoroughly cleanse the interiors thereof. In the prior devices, the bottle was usually inverted over a water nozzle and a continuously flowing stream of water was projected from said nozzle into said bottle. That portion of the stream of water which entered the bottle at the beginning of the washing operation struck the inside face of said bottle with much force, but this water would immediately flow downwardly to the neck of the bottle and, because of the restricted opening in said bottle neck, would collect there. This collection of water in the neck of the bottle would tend to act as a seal to prevent the incoming water from being injected into said bottle, and as it would be necessary for the stream of water to force its way through the water in the neck of the bottle, much of the force of said stream would be dissipated. In the device disclosed in the present application, the streams of water which are injected into the bottles flow intermittently into said bottles, there being an interval between jets of water to permit said water to drain from the bottles, hence the objections set forth above are eliminated.

Another object is to produce a simple automatic means for controlling the flow of water to the different washing devices of a bottle-washing machine.

With the foregoing and other objects in view, the invention comprises the novel construction, combination and arrangement of parts hereinafter more specifically described and illustrated in the accompanying drawings wherein is shown the preferred embodiment of the invention. However, it is to be understood that the invention comprehends changes, variations and modifications which come within the scope of the claims hereunto appended.

Fig. I is a plan view of our improved

bottle washing machine with the housing removed. 55

Fig. II is a side elevation of the machine shown in Fig. I.

Fig. III is a view similar to Fig. II showing the opposite side of the machine. 60

Fig. IV is a longitudinal section through the machine.

Fig. V is an end elevation of the machine.

Fig. VI is an enlarged fragmentary side elevation showing the mechanism for operating the water-controlling valve and the means for automatically stopping the machine. 65

Fig. VII is an enlarged fragmentary section showing the receiving end of the machine, and the mechanism for adjusting the positions of the spray pipes. 70

Fig. VIII is an enlarged plan view of the water-controlling valve of the machine.

Fig. IX is a horizontal section of the valve 75 shown in Fig. VIII.

Fig. X is a section on line X—X of Fig. IX.

Fig. XI is an enlarged plan view of a portion of one of the bottle-supporting members 80 showing a portion of one of the chains to which said member is attached.

Fig. XII is a section on line XII—XII of Fig. XI.

Fig. XIII is a section through the electric 85 switch forming a part of the electrical system of the machine.

Fig. XIV is a fragmentary detail showing the clutch and associated mechanism for controlling the operation of the bottle washing machine. 90

According to the present embodiment of our invention, our bottle washing machine is intended and adapted to operate in connection and in unison with a bottle soaking machine of the type in which the bottles are carried in bottle holders fixed to endless chains, the bottles in said bottle holders being passed through a solution to soak said bottles. In the present instance, and as a part of a complete system, the bottles are automatically delivered from the bottle holders of the soaking machine to our bottle washing machine, which acts upon and thoroughly cleanses the bottles without the intervention of any manual operations whatever. However, it will be understood that it is not essential that our bottle washing

machine should thus work in conjunction with a bottle soaking machine, but that the bottles may be fed to our bottle washing machine by hand or in any other way, as 5 found desirable.

Referring to the drawings, S designates the soaking machine which, as has been stated, is used in conjunction with our bottle washing machine. As the soaking machine 10 forms no part of the present invention, it will not be necessary to describe its details of construction, it being sufficient to say that said soaking machine is provided with endless chains C which are supported by, 15 and travel over, suitable sprocket wheels W. The endless chains C are provided with bottle holders H in which the bottles are carried. The bottle holders H of the soaking machine travel in the direction indicated 20 by the arrow in Fig. IV of the drawings, and each of said bottle holders is provided with a gate G which retains the bottle in place within the bottle holder until said bottle holder is in the proper position to dis- 25 charge said bottle into the bottle washing machine when said gates G are lifted, thus permitting the bottles to pass from said bottle holders.

Referring now to our improved bottle 30 washing machine, A designates a reservoir which is provided with side and end walls and an inclined bottom A'. The reservoir A is supported in any suitable manner, as, for instance, by attaching one end of said 35 reservoir to the soaking machine S and supporting the other end thereof by means of legs L which rest upon the floor. The end walls and bottom of the reservoir A are preferably formed of sheet metal, said end walls and bottom being supported by the side members B, to which said end walls and bottom are attached by means of fastening devices B'.

Supported by the side members B of the 40 reservoir A is a housing 1 comprising side walls 2 and a top 3, said top comprising a fixed portion 3' and hinged portions 4 and 5, said portions 4 and 5 being hinged at the points indicated by the reference character 45 50 55 60 65 70 75 80 85 90 95 100 105 110 115 120 125 130 135 140 145 150 155 160 165 170 175 180 185 190 195 200 205 210 215 220 225 slideway for the bottles being conveyed to the bottle holders of the washing machine, said slideway being provided with dividing members 30 whereby inclined chutes 31 are 5 provided which are in continuation of the inclined chutes 16'.

In describing briefly the construction of the soaking machine S, it was stated that said machine was provided with endless 10 chains which operated over sprocket wheels. The upper sprocket wheels of the soaker are mounted on a shaft 32 which is actuated by the same mechanism which drives the washing machine. This mechanism will be described later in this specification, but it is sufficient at the present time to know that the shaft 32 rotates when the washing machine is in operation. The operating arms 22 which support the inclined table 16, as has 15 been stated, are pivotally supported by a pair of members 23, there being a pair of stud shafts 34 to which said operating arms 22 are rigidly fixed extending through bearings in said members 23. One of the stud 20 shafts 34 extends through and beyond the associated supporting member, and to this extended portion of said stud shaft an arm 35 is fixed. The arm 35 extends rearwardly from said shaft 34 and is provided with an 25 upturned portion 35' (Fig. II). Fixed to the shaft 32 is a star wheel 36, said star wheel being adapted to cooperate with the upturned portion of the arm 35 in such manner as to cause the end of said arm to be depressed by the projections 36' when said star 30 wheel is rotated.

The endless conveyor of the bottle washing machine is intermittently driven, and we will now describe how this intermittent motion is obtained. 37 designates a shaft 40 which extends transversely of the washing machine, said shaft being supported in suitable bearings in the side walls 2 of the housing 1. The shaft 37 is provided at one of its 45 ends with a gear wheel 38, said gear wheel being loosely mounted on said shaft.

Located adjacent to the shaft 37 is an auxiliary shaft 39 which supports a pinion 40 adapted to mesh with the gear 38 on the shaft 37. The shaft 39 is mounted to rotate in a bearing 39' which is supported by one of the bearings of the shaft 37 (Fig. XIV). Surrounding the shaft 39 is a sleeve 39^a, said sleeve being fixed to the bearing 39', thus the shaft 39 may rotate within the non-rotatably held sleeve 39^a. Fixed to the shaft 39 at an end thereof and adapted to rotate with said shaft is a clutch member 41, said clutch member being intended to function in a manner which will be subsequently pointed out. Mounted on the sleeve 39^a is a pulley 42, said pulley being loosely mounted on said sleeve whereby said pulley may rotate about same and may also move longitudinally thereof. 55 The pulley 42 has fixed to it a clutch member

43 similar to the clutch member 41 on the shaft 39, and these clutch members 41 and 43 are adapted to be brought into cooperation with each other so that said pulley 40 and said clutch members 43 and 41 may rotate as 60 a unit. The cooperation of the clutch members 41 and 43 is effected by means of operating mechanism comprising a shaft 44 which extends longitudinally of the machine, said shaft being provided at one end with an operating handle 44' whereby said shaft may be rotated about its axis. Pivottally secured to a side wall 2 of the housing 1 is an arm 45, said arm being provided at its upper end with a bifurcated portion 45' which partially surrounds the hub of the pulley 42, said hub having an annular groove which receives the ends of said bifurcated portion of said arm 45. The arm 45 is also provided with a bifurcated portion 45^a at its lower end, said bifurcated portion 45^a being associated with a finger 44^a on the shaft 44 in a manner to be hereinafter described. The pulley 42 is driven by a belt 46, which in turn is driven by any suitable prime mover, such, for 70 instance, as the motor M in the drawings. From the foregoing it is plain that if the clutch members 41 and 43 are disengaged and the pulley 42 is being driven, said pulley would rotate idly about the sleeve 39^a without affecting the other mechanism, but if the shaft 44 were rocked so as to cause the end of the finger 44^a on said shaft to move in an arc of a circle above said shaft 44, said finger 44^a would engage the legs of the bifurcated portion 45' to rock the arm 45 on its pivot. The 75 operation of the mechanism just described will be apparent after a study of Fig. XIV of the drawing. If the parts were in the position in which they are shown in Fig. XIV and the shaft 44 were rotated about its axis, the finger 44^a would engage the leg of said bifurcated portion which is within the arc described by the outer end of said finger and would move the lower end of said arm 80 laterally, thus engaging or disengaging the clutch members 41 and 43. The finger 44^a remains in engagement with the legs of the bifurcated portion 45' at all times, hence the danger of said parts being accidentally moved 85 is eliminated. When the arm 45 is operated to move the pulley and its associated clutch member longitudinally of the sleeve 39^a so that said clutch member 43 engages the clutch member 41, said clutch member 41 and its 90 associated pinion 40 will be rotated with the pulley 42. The gear wheel 38 is mounted loosely on the shaft 37 and said gear wheel 38 is associated with a train of gears 38^a, 38^b, 38^c, and 38^d whereby the speed of the shaft 95 37 is reduced.

Secured to the end of the shaft 37, opposite to the end on which the gear wheel 38 is mounted, is a crank arm 47, said crank arm being provided with a crank pin having an 100

anti-friction roller 47' extending outwardly from said arm at one end thereof. Mounted at the end of the shaft 8, which forms a part of the endless conveyor of the washing machine, is a wheel 48 having a plurality of radial slots 48' and arcuate faces 49, as shown in Fig. III. 50 designates a disk secured to the shaft 37 adjacent to the crank arm 47, the peripheral face of the disk 50 being adapted to engage any one of the arcuate faces 49 of the wheel 48. The crank pin on the arm 47 travels in the path indicated by the dotted circle in Fig. III, and when the crank pin enters one of the radial slots 48' the movement of the crank pin will be transmitted to the slotted wheel 48. At this time a portion of the slotted wheel 48 enters a recess 50' in the disk 50, and when the crank pin passes from the slot 48' one of the arcuate faces 49 engages the periphery of the disk 50 to lock the slotted wheel and prevent same from rotating. Obviously, the mechanism just described will move the shaft 8 intermittently and carry the bottles step by step away from the intake end of the washing machine.

Mounted on the shaft 37 at an outer end thereof is a sprocket wheel 51 (Fig. III), and mounted on the shaft 32 of the soaking machine is a comparatively large sprocket wheel 52. A sprocket chain 53 operates over the sprocket wheels 51 and 52 so that when the shaft 37 is rotated in the manner already described, the chain 53 will impart a like rotary movement to the shaft 32.

It may be well to describe the operation of the machine thus far described. Assume that the motor M is in motion; this, because of the belt 46, will rotate the pulley 42. 40 Assume, also, that the shaft 44 was rocked so as to move the clutch member 43 into engagement with the clutch member 41, thus transmitting the rotary movement of the pulley 42 through the pinion 40 and the gear wheels 38, 38^a, 38^b, 38^c and 38^d to the shaft 37. The rotation of the shaft 37 is continuous while the machine is in motion, and this continuous motion of said shaft 37 is transmitted by the sprocket chain 53 to the shaft 32 of the soaking machine, hence, whenever the washing machine is in operation the soaking machine is likewise in motion. It has been stated that the shaft 37 is constantly rotating while the machine is in operation, but by the use of the Geneva movement K illustrated in Fig. III, an intermittent or step by step movement is transmitted from said constantly driven shaft 37 to the drive shaft 8 of the endless conveyor.

60 The soiled bottles are placed in the bottle holders of the soaking machine and are carried through the soaking solution, said bottle holders moving in the direction indicated by the arrow in Fig. IV, and when said bottle holders reach the proper position the gates

thereof are lifted and the bottles are discharged into the inclined chutes 16', said bottle holders of the soaking machine and said inclined chutes being in alinement. At this stage of the operation there is a bottle 70 in each of the inclined chutes 16', the necks of said bottles being in engagement with the bumper 24, as shown in Fig. IV. The shaft 32, it will be remembered, is provided with a star wheel 36 which engages the upturned 75 portion 35' of the arm 35. The shaft 32 is constantly rotating, and as each successive projection on said star wheel 36 engages the arm 35 said arm will be depressed. The arm 35 is secured to one of the stud shafts 34 so that when said arm is depressed said shaft will be rocked, and as the operating arms 22 are secured to the stud shafts 34 and as said operating arms are secured to the inclined 80 table 16, the depression of the arm 35 will 85 move the inclined chutes 16' upwardly in an arc of a circle about the shaft 34. The upward movement of the inclined chutes 16' will continue until the necks of the bottles therein have passed beyond the upper edge 90 of the bumper 24, when said bottles will slide over said bumper into the inclined chutes 31 and from said chutes into the bottle pockets 14 of the washing machine which are in position to receive said bottles. As 95 soon as the bottles are located in the pockets 14 of the washing machine, the endless conveyor thereof starts to move and said bottles are carried to the first washing position, where they are again stopped. The water- 100 controlling mechanism will now be described.

60 designates a pair of water-conducting pipes which extend transversely of the washing machine, each of said pipes being provided with a plurality of apertures 60', said apertures being so located that one of them is immediately below each bottle-receiving pocket in one of the associated cross members 13. The pipes 60 are supported by connecting members 61, one of which is located 105 at each end of said pipes. 62 indicates hangers pivotally secured to the side walls of the housing 1. The connecting members 61 are pivotally secured to the pivoted hangers in any suitable manner. The hangers 62 110 are provided with portions 62' which extend below the connecting member 61. Mounted on the shaft 9 of the endless conveyor of the washing machine, at each end thereof, is a member 64, said member having a hub portion which surrounds said shaft 9 and a portion extending in a direction toward one of the pivoted hangers 62. The outer end portion of the member 64 is provided with a plurality of apertures 65 which receive a lug 115 66 on the portion 62' of the adjacent hanger 62, consequently, if the shaft 9 were shifted longitudinally of the machine, the pivoted hangers, connecting members and pipes would be shifted with said shaft, the open- 120 125 130

ings in the wall of the housing 1 through which said pipes extend being elongated to permit movement of said pipes. The necessity for providing a means for adjusting the 5 pipes 60 with the shaft 9 is occasioned by the fact that the chains of the endless conveyor of the washing machine are liable to stretch, in which event the apertures 60' in the water-conducting pipes 60 would not register with the bottle-receiving pockets. To prevent this we locate the bearings 9' in which the shaft 9 is journaled in elongated openings 67 in the side walls 2 of the housing 1. 68 designates lugs formed on said 10 walls 2, said lugs being adapted to receive screws 69 which bear against said bearings 9'. From the foregoing it is apparent that in the event the chains 12 become loose said 15 looseness may be taken up by manipulating the screws 69, thus moving the bearings 9' in a direction away from the shaft 8, and due to the fact that the pipes 60 are connected to said shaft 9 said pipes will move a 20 proportional distance, thereby insuring the proper alinement of said pipes relative to the 25 bottle-receiving pockets 14.

Located immediately below the cover of the housing 1 is a pair of water-conducting pipes 70 similar to the pipes 60, said pipes 30 70, like the pipes 60, being provided with a plurality of discharge apertures 70'. The pipes 60 and 70 are connected to a main water supply pipe, and a means which will now be described is provided to control the 35 flow of water so that water under pressure will be intermittently conducted through said pipes.

71 designates a water-controlling valve which comprises a stationary valve housing 40 72 and a rotatable member 73 within said valve housing. The valve housing includes a removable portion 74 which screws onto the associated portion of said housing, said removable portion being provided with a 45 threaded opening 74', adapted to receive a water-conducting pipe 75. The valve housing 72 is provided with a water passageway 76 which leads upwardly in said housing and a water passageway 77 which leads downwardly therein, and said valve housing is provided with threaded openings in the wall of 50 said housing communicating with said passageways 76 and 77 whereby a pipe 78 may be screwed in the threaded opening associated with the passageway 76, thus conducting the water passing through said passageway to the water pipes 70, and a pipe 79 may be screwed into the threaded opening associated with the passageway 77 to conduct the 55 water passing through said passageway to the pipes 60. The rotating member 73 within the valve housing is provided with a plurality of apertures 73', which are adapted to be successively alined with the passageways 60 65 76 and 77. Mounted to rotate in a suitable bearing within the valve housing is a shaft 80, the rotatable member 73 being secured to said shaft and being adapted to rotate therewith. Mounted on the shaft 80 is a sprocket wheel 81, and mounted on the shaft 37 is a 70 similar sprocket wheel 82. Associated with the sprocket wheels 81 and 82 is a sprocket chain 83. The operation of the water-controlling mechanism is as follows: Assuming that the machine is in operation, the shaft 75 37 will, of course, be rotating due to the operation of mechanism already described. Because of the sprocket wheels 81 and 82 and the sprocket chain 83 the rotary movement of said shaft 37 will be transmitted to the shaft 80 supported in the valve housing 72. It will be seen by referring to Fig. IX of the drawing that the rotatable member 73 separates water passageways 76 and 77 from the water inlet opening 74'. The apertures in the rotatable member 73 are so located that when one of said apertures is aligned with one of the water passageways, the solid portion of said rotatable member will close the other passageway (Fig. IX), hence 80 water entering the valve housing through the opening 74' will either pass into and through the passageway 76 and be conducted to the pipes 70 or will pass into and through the passageway 77 and be conducted to the pipes 60. In the latter event, said water will pass into and through a passageway 84 in one of the connecting members 61 which passageway communicates with the pipes 60. The motion of the bottles through the machine is an intermittent one and the water-controlling valve is so timed that while the bottles are at rest in the machine one of the apertures in the rotating member 73 moves into alinement with the passageway 77, hence 85 streams of water are injected from the pipes 60 into the interiors of two rows of bottles. The rotatable member 73 is constantly rotating, however, and said aperture will pass beyond said passageway 77 and the flow of water therethrough will be stopped. As one of the apertures 73' passes from alinement with the passageway 77 another aperture passes into alinement with the passageway 76, hence the water will be conducted to the pipes 70 and will be showered down on the outside faces of the bottles. The diverting of the water from the pipes 60 permits the water which had been injected into the interior of the bottles to drain therefrom, so that when the water is again injected from 90 said pipes into the interior of said bottles, there will be no collection of water in the necks of the bottles to prevent said incoming streams from passing into the bottles with full force. From the foregoing it is plain that streams of water are intermittently injected into the interior of the bottles and showered down on the outside faces of said bottles, it also being apparent that the wash-

ing machine and water-controlling valve are so timed that the water is injected intermittently into the bottles while said bottles are stationary, there being several distinct jets of water injected into each bottle during each period of rest thereof. One of the pipes 70 is located immediately above the bottle-receiving mechanism of the machine whereby the bottles in said receiving mechanism are intermittently showered with water, whereby they are preliminarily cleaned.

85 designates a bottle discharge table onto which the cleaned bottles slide from the pockets 14 when said pockets reach the proper positions. Said discharge table 85 comprises an inclined member 86 which is provided with a plurality of upwardly extending partitions 87 whereby a plurality of inclined chutes are provided, each of which is in such position as to be in alignment with successive bottle-receiving pockets 14. The discharge table 85 is provided with a stop member 88 which stops the bottles after they have reached their proper positions on the member 86.

89 designates a plurality of fingers, one of which is below a portion of each of the inclined chutes of the discharge table 85, there being an opening in each of said chutes in which the fingers 89 operate. All of the fingers 89 are secured to a transverse shaft 90, said shaft being provided at one of its ends with an arm 91. Fixed to the constantly rotating shaft 37 is an arm 92, said arm being connected to the arm 91 by means of a connecting rod 93. The connecting rod 93 is pivotally connected to the arm 92 and is also pivotally connected to the arm 93 by means of the swivel joint 94.

40 Located adjacent to the discharge table 85 is an endless conveyor 95, the purpose of said endless conveyor being to convey the bottles away from the washing machine after said bottles have been washed.

45 In the operation of the discharge mechanism of our machine, the constantly rotating arm 92 through the connecting rod 93 imparts an oscillating motion to the arm 91 and thereby rocks the shaft 90. The rocking of the shaft 90 causes the fingers 89 to move in an arc of a circle above the shaft 90, and as said fingers are in contact with the bottles the upward, arcuate movement of said fingers will stand said bottles on their bottoms on the shelf 96, said shelf being divided into a plurality of compartments open at both ends and each of said compartments being in alignment with one of the inclined chutes of the discharge table. The row of bottles thus placed in the compartments on the shelf 96 will be moved onto the endless conveyor 95 by the next row of bottles and will be carried away by said endless conveyor.

60 65 To prevent the bottles being dropped

heavily on the inclined table 85 and to guide said bottles to said inclined table, we provide a plurality of members 97, said members being pivotally mounted on a transverse rod 98 supported by the housing 1. 70 Each of the pivoted members 97 is located in such position that it will be engaged by successive bottles and each of said members is provided with a counterbalance weight 97'. In operation each of the bottles of a row about to be discharged onto the discharge table 85 will engage the blade of one of the pivoted members 97, and said blade will guide said bottle to its position within one of the inclined chutes of the discharge table. 75 The counterbalance weights on the pivoted members will prevent the bottles from falling heavily on the discharge table 85, said bottles being allowed to settle gently thereon.

In the operation of the machine, it may happen that one of the bottles will stick in the pocket 14 and said bottle will not be discharged onto the discharge table 85. In the absence of safety mechanism, this bottle would strike the end of the inclined table 85, and as the bottle pocket moved on, either the bottle or some part of the machine would be broken. To prevent this occurrence we provide safety mechanism which will now be described.

The shaft 90 extending transversely of the machine at the rear thereof is adapted to support the inclined discharge table 85, there being arms 100 which are secured to the lower face of said inclined table, said arms having hub portions adapted to surround said shaft. 101 designates arms which are fixed to a shaft 102, said arms being adapted to support the upper end of said discharge table. 103 designates a lever which is fixed to an outer end of the shaft 102, said lever being held in a horizontal position by a coil spring 104, one end of which is fixed to the lever 103 and the opposite end of which is fixed to the frame of the machine. The lever 103 is provided with a laterally extending portion 103'. Mounted on the shaft 44 is an arm 105, said arm being adapted to rotate with said shaft 44 and being provided with an extension 106 which contacts with the lower face of the laterally extending portion 103' of the lever 103. In the event that a bottle becomes stuck in a bottle pocket so that said bottle strikes the inclined discharge table 85, said discharge table will be depressed by said bottle and the downward movement of said table against the arms will oscillate the shaft 102, and as the free end of the arm 103, which is secured to said shaft, is in contact with the arm 105, said arm will be oscillated thereby rocking the shaft 44 and through the mechanism already described disengage the clutch members 41 and 43, thus stopping the machine.

60 65 70 75 80 85 90 95 100 105 110 115 120 125 130 In the event that the bottle washing ma.

- chine is stopped by the operation of the mechanism just described, it is also desired to stop the endless conveyor 95 and this is accomplished by breaking the electric circuit by which electric energy is conducted to a separate motor (not shown) by which said endless conveyor is actuated. The mechanism for controlling said endless conveyor will now be described.
- 10 107 designates an electrical contact member secured to the shaft 44, there being a collar 108 secured to said shaft to which said contact member is secured. 109 designates a pair of contact members which are secured to 15 a block of insulating material fixed to the switch housing 110. Electricity-conducting wires 111 are connected by means of bolts 112 to said contact members 109, said electricity-conducting wires constituting the electric 20 circuit by which electric energy is conducted to the motor which operates the endless conveyor 95. The electrical contact members 109 are spaced apart so that the electric circuit is normally broken, but when the 25 parts are in the positions shown in Fig. XIII the electrical contact member 107 will be in contact with both of said contact members 109, hence the electrical current will cross the gap between said members 109 by passing 30 through the member 107.
- When the shaft 44 is rocked either by the 35 operation of the safety mechanism already described or by being manually operated, the electrical contact 107 will be moved out of contact with the contact member 109 whereby the flow of electricity through the electricity-conducting wires 111 will be interrupted, thus stopping the endless conveyor 95.
- 40 As will be seen by referring to Fig. IV, a body of water collects in the reservoir of the washing machine, this body being water that has been previously used to wash bottles. The level of the body of water referred to is 45 determined by an overflow pipe 113 (Fig. III). The bottles which are passed into the bottle washing machine to be washed often have old labels clinging to them, and it may happen that one or more of these labels may 50 be washed to a position at the mouth of one of the bottle pockets whereby the entrance of a bottle into said pocket is interfered with. To prevent this we maintain the level of the body of water within the reservoir at 55 such height that the mouths of said bottle pockets will be drawn through said water, thereby keeping same free from old labels. The passage of the bottle pockets through the water within the reservoir in the manner described will cause a movement of said water in a direction toward the bottle-receiving end of the machine and this movement of said water would cause labels and other matter washed from the bottles to be moved 60 toward said bottle-receiving end of the ma-
- chine. To clean the reservoir we provide an opening 114 which may be covered by a removable handplate 115, said opening being located at the lowest point of the reservoir and at the point toward which the labels and other matter are moved by the movement of the water.
- The water-conducting pipe 75 by which water is conducted to the automatic valve 71 is provided with a cut-off valve 116 which is controlled by the shaft 44, said shaft being provided with an arm 117 which oscillates with said shaft 44. The valve 116 is provided with a rotatable valve stem 118 to which is fixed an arm 119. 120 designates a connecting rod, one end of which is pivotally connected to the arm 117 and the other end of which is pivotally connected to the arm 119 on the valve stem 118. When the shaft 44 is rocked, the valve stem, through the operation of the arms 117 and 119 and the connecting rod 120, will be oscillated whereby the flow of water through the pipe 75 will be controlled.
- The pivotally supported members 97 which are intended to prevent the bottles from being dropped heavily on the inclined discharge table 85 are of such lengths that they will function as intended regardless of the size of the bottles being washed. Said bottles of different sizes would contact with the blades of the members 97 at different points, but the operation of said members would be the same. This feature is an important one, in that it obviates the necessity of providing members which are adjustable so as to be operable with different sized bottles.
- We claim:
1. A bottle-washing machine comprising an intermittently movable bottle holder adapted to hold an inverted bottle, a water-discharging device comprising a water conductor having a discharge aperture adapted to discharge water into said bottle, a water-controlling means comprising a valve in said conductor provided with rotatable means whereby water is permitted to pass through said valve to said aperture, and actuating means for said rotatable means timed with relation to the movement of said bottle holder whereby water is caused to flow intermittently into said bottle during each period of rest thereof.
2. A bottle-washing machine comprising an intermittently movable bottle holder, a spray head adapted to discharge water into the bottle carried by said holder, a spray head adapted to discharge water against the exterior of said bottle, and water-controlling means comprising a valve housing provided with a plurality of passageways in communication with said spray heads and rotatable means within said valve housing controlling the flow to said spray heads whereby water

- may be directed successively through said passageways, and actuating means for said rotatable means timed with relation to the movement of said bottle holder whereby water is caused to flow intermittently into and onto said bottle during each period of rest thereof.
3. A bottle-washing machine comprising a bottle holder, a water-discharging device adapted to discharge a stream of water into the bottle, a second water-discharging device adapted to discharge a stream of water against the exterior of said bottle, and water-controlling means comprising a valve casing provided with a plurality of passageways each of which communicates with one of the aforesaid water-discharging devices, a rotatable shaft within said valve casing, a disk provided with an aperture formed therethrough mounted on said shaft within the valve casing, and means whereby said shaft may be rotated to cause said aperture in said disk to be brought successively into registration with said passageways.
- 15 4. A bottle-washing machine having a bottle-carrying mechanism comprising an endless conveyor, a water-discharging device adapted to discharge streams of water into the bottles, means whereby looseness in the bottle-supporting portion of said endless conveyor may be taken up, and means cooperating with said water-discharging device and controlled by said last mentioned means whereby said water-discharging device may be kept in alinement with the bottles on said endless conveyor.
- 20 5. A bottle-washing machine having a bottle-carrying mechanism comprising supporting shafts, endless chains supported by said shafts, and bottle-holding devices carried by said chains, a water-discharging device adapted to discharge streams of water into the bottles, means whereby one of said supporting shafts may be moved away from the other shaft to remove looseness from the bottle-supporting portion of said endless chains, and means cooperating with said movable shaft and said water-discharging device whereby said water-discharging device may be moved a corresponding distance to maintain the alinement between said water-discharging device and said bottle-holding devices.
- 25 6. A bottle-washing machine having a bottle-carrying mechanism comprising supporting shafts, endless chains supported by said shafts, and bottle-holding devices carried by said chains, a water-discharging device adapted to discharge streams of water into the bottles, means whereby one of said supporting shafts may be moved away from the other shaft to remove looseness from the bottle-supporting portion of said endless chains, and means cooperating with said movable shaft and said water-discharging device whereby said water-discharging device may be moved a corresponding distance to maintain the alinement between said water-discharging device and said bottle-holding devices.
- 30 7. A bottle-washing machine having a bottle-carrying mechanism comprising supporting shafts, endless chains supported by said shafts, and bottle-holding devices carried by said chains, a plurality of water-discharging pipes adapted to discharge streams of water into said bottles, members connecting the water-discharging pipes together, pivoted hangers supporting said water-discharging pipes and connecting members, means whereby one of said supporting shafts may be moved away from the other shaft to remove looseness from the bottle-supporting portions of said endless chains, and means comprising a connecting link extending from said movable shaft to one of said pivoted hangers whereby said water-discharging pipes may be moved a corresponding distance to maintain the alinement between said water-discharging pipes and said bottle-holding devices.
- 35 8. A bottle washing machine comprising a bottle carrier adapted to hold an inverted bottle, said bottle carrier being movable intermittently to hold the bottle at rest in a washing position, and means whereby jets of water are successively discharged into and drained from the bottle while the latter is held in said position, said means including a water conductor having a discharge aperture for the discharge of said jets, a valve to control the delivery of water through said aperture, and actuating means for said valve timed with relation to the movement of said bottle carrier whereby water is intermittently delivered to said aperture while the bottle is held in said position.
- 40 9. A bottle-washing machine comprising a bottle-carrying mechanism comprising supporting shafts, endless chains supported by said shafts, and bottle-holding devices carried by said chains, a water-discharging device adapted to discharge streams of water into the bottles, means whereby one of said supporting shafts may be moved away from the other shaft to remove looseness from the bottle-supporting portion of said endless chains, and means cooperating with said movable shaft and said water-discharging device whereby said water-discharging device may be moved a corresponding distance to maintain the alinement between said water-discharging device and said bottle-holding devices.
- 45 10. A bottle-washing machine comprising a bottle-carrying mechanism comprising supporting shafts, endless chains supported by said shafts, and bottle-holding devices carried by said chains, a water-discharging device adapted to discharge streams of water into the bottles, means whereby one of said supporting shafts may be moved away from the other shaft to remove looseness from the bottle-supporting portion of said endless chains, and means cooperating with said movable shaft and said water-discharging device whereby said water-discharging device may be moved a corresponding distance to maintain the alinement between said water-discharging device and said bottle-holding devices.
- 50 11. A bottle-washing machine comprising a bottle-carrying mechanism comprising supporting shafts, endless chains supported by said shafts, and bottle-holding devices carried by said chains, a water-discharging device adapted to discharge streams of water into the bottles, means whereby one of said supporting shafts may be moved away from the other shaft to remove looseness from the bottle-supporting portion of said endless chains, and means cooperating with said movable shaft and said water-discharging device whereby said water-discharging device may be moved a corresponding distance to maintain the alinement between said water-discharging device and said bottle-holding devices.
- 55 12. A bottle-washing machine comprising a bottle-carrying mechanism comprising supporting shafts, endless chains supported by said shafts, and bottle-holding devices carried by said chains, a water-discharging device adapted to discharge streams of water into the bottles, means whereby one of said supporting shafts may be moved away from the other shaft to remove looseness from the bottle-supporting portion of said endless chains, and means cooperating with said movable shaft and said water-discharging device whereby said water-discharging device may be moved a corresponding distance to maintain the alinement between said water-discharging device and said bottle-holding devices.

In testimony that we claim the foregoing we hereunto affix our signatures.

JOSEPH W. DAWSON.
JAMES L. HEROLD.
